UNITED STATES PATENT OFFICE.

TAYLOR McDougall, of Pasadena, and SULLY RUSSO, of Los Angeles, California; said McDougall assignor to said Russo.

RECORD-FILE.

1,379,030.

Specification of Letters Patent. Patented May 24, 1921.

Application filed April 2, 1918. Serial No. 226,138.

To all whom it may concern:

Be it known that we, TAYLOR McDougall and SULLY Russo, citizens of the United States, residing at Pasadena and Los Angeles, respectively, in the county of Los Angeles and State of California, have invented a new and useful Record-File, of which the following is a specification.

This invention pertains to files more especially of the character designed to hold phonograph records of the disk type and an object of the invention is to produce a record file of this character of comparatively simple and inexpensive construction.

Another object is to produce a file for comparatively great strength for the amount of material used in its construction so that rough handling thereof will not destroy its usefulness.

Another object is to provide a record file in which the partitions are formed of wire.

Another object is to provide a simple form of supporting members for the records.

Other objects and advantages will appear in the subjoined detail description.

The accompanying drawings illustrate the invention:

Figure 1 is a perspective view of a record file constructed in accordance with the provisions of this invention.

Fig. 2 is a sectional elevation of the file.

Fig. 3 is an enlarged fragmental elevation partly in section on line indicated by x^3-x^3 , Fig. 2, some of the partitions being omitted.

Fig. 4 is a plan view of one of the levers or record supporting members.

Fig. 5 is a sectional elevation of a modified form of the invention, the view being analogous to that shown in Fig. 2.

Fig. 6 is a cross section of a partition-forming wire, a covering therefor also being shown in section.

There are provided end members 1, 2 of any suitable shape, in Fig. 1 said members being triangular and in Fig. 5 the end members being rectangular. From the nature of the view in Fig. 5 only one end member can be seen. Connecting the end members together are partition-supporting rods 3, 4, 5.

In Fig. 5 there is a fourth partition-supporting rod indicated at 6. The rods 3 to 6 inclusive are fastened to the end members 1, 2 by screws 7 or equivalents, the screws being screw-threaded into the ends of the

rods so that the end members 1, 2 are embraced between the ends of the rods and the heads of the screws. The rods 3 to 6, inclusive, may be provided with notches 8 at intervals therealong and said notches are engaged by partitions formed of wires; each partition being formed of a single piece of wire and comprising a front upright member 9, a downwardly and rearwardly slanting member 10 and a downwardly and forwardly slanting member 11 as in Fig. 2, or, in the case of Fig. 5, comprising a front vertical member 9, a rear vertical member 12 and a downwardly and forwardly slanting member 13. The member 9 extends from the rod 3 to the rod 4; the member 10 in Fig. 2 extends from the rod 3 to the rod 5; the member 11 in Fig. 2 extends from the rod 4 to a point intermediate the ends of the member 10; the member 12 in Fig. 5 extends from the rod 5 to the rod 6; and the member 13 in Fig. 5 extends from the rod 4 to the rod 6.

The lower rear end of the wire of each partition is bent around the rod 5 as indicated at 14 and, in Fig. 2, said wire extends aslant forward and upward, thence over the rod 3 and through one of the notches 8 in the rod 3, thence downward beneath the rod 4 and through one of the notches 8 thereof and thence aslant upward and rearward where the end is fastened by any suitable means to the member 10. The end may be fastened by solder, not shown, or may be spot welded. Thus the partition in Fig. 2 is in the form of a triangle, excepting that the base member is omitted. In the form of the invention shown in Fig. 5 the wire of each of the partitions passes upward over the rod 6 and through one of the notches thereof, thence downwardly and forwardly beneath the rod 4 and through one of the notches thereof, thence upwardly over the rod 3, and is bent at 15 around said rod 3. Thus in Fig. 5 each partition is in the form of the letter N.

To improve the appearance of the file, shown in Fig. 2, there may be provided a top strip 16 of channel shape, the flanges of the channel being bent downward on opposite sides of the rod 3. The strip 16 covers the slots in the rod 3 and preferably the front flange 17 of said strip is bent inward into engagement or close to the members 9 of the partitions. Also the bottom strip 18

may be provided with a flange 19 and said bottom strip may be bent inward into engagement with or close to the partition member 9. The end portions of the strips 5 16, 18 are turned over on the outside of the end members 1, 2 as indicated at 20 and the screws 7 pass through said turned over portions. In the form of the invention shown 10 in Fig. 5 there is provided a top 21, rear wall 22 and bottom 23 all suitably connected to the end members, the forward margins of the top and bottom forming strips analogous in function to the strips 16, 18.

In Fig. 2 there is provided a rear L-shaped member 24 bent to form a channel 25 along its upper edge and in said channel is inserted a buffer 26 formed of a strip of suitable material as, for instance, felt or the like adapted to engage the rear edges 20 of the records, not shown. The L-shaped member 24 is provided with turned over portions 27 through which the associated screws 7 pass so as to fasten the L-shaped member to the end members 1, 2.

25 In Fig. 2 the upper surface of the lower leg of the L-shaped member 24 is provided with a buffer 27.

Mounted in the end members 1, 2 at its opposite ends is a shaft 28, said shaft being 30 nearer the front margins of said end members than the rear margins. Pivoted on the shaft 28 is a series of record holding members in the form of levers 29, there being a lever between each two adjacent partitions 35 and also between the endmost partitions and the end members 1, 2. These levers may be constructed as follows: The longitudinal marginal portions of the levers 29 are upturned to form flanges 30 which extend in 40 spaced relation from near the forward ends of the levers to a substantial distance from the rear ends thereof where said flanges are bent inwardly at 31 to form narrower portions or fingers at the rear ends of the levers. By this construction the rear end portions of the levers are given a rounded relatively narrow construction so that friction between them and the wire partitions will be minimized, said narrower portions of the 45 levers extending between adjacent members 10 of the partitions and being free from said members. The levers 29 are normally inclined slightly rearward and downward and the fingers 31 rest on the buffer 27.

50 This buffer 27' prevents noisy operation when the levers are released after operation. Each lever 29 terminates at its forward end with a flat circular disk provided with a medial perforation 32 to receive the clamping prongs 33 of a key button 34 which may be of any suitable construction. The prongs 33 are bent under the levers 29 so as to firmly hold the buttons 34 on the levers. Each lever 29 may be provided with a downwardly 55 pressed rib 35 to strengthen the outer end

of the lever. Each lever is provided between the flanges 30 with a downwardly bent portion 36 which is curled under the bottom of the lever to form an openable and closable eye engaging the shaft 28, as clearly 70 shown in Fig. 2. When the file is being assembled, the levers 29 may all be assembled on the shaft 28 before fastening said shaft in place, but it is clear that if any one of the levers should become bent or if it should 75 become desirable to remove any one of the levers for any reason whatsoever, the lever may be removed from the shaft 28 by first bending open the curled portion 36. The levers 29 described may be readily manufactured at comparatively low cost since they are stamped from sheet metal with practically no waste of material.

In practice, to use the record file above described, if it be desired to place a record 80 in the file, the record will be presented edge-wise between two adjacent partition members 9 and will be allowed to rest on the appropriate lever 29. Then the record will be thrust rearwardly and as soon as its center 90 passes rearward of the shaft 28 the record, owing to the action of gravity thereon, will roll down the inclined lever 29 until it rests against the buffer 26. To remove a record from the file, the operator will press down 95 on the appropriate button 34, thus tilting the lever 29 forward and downward, whereupon the record will roll forward and can be readily grasped by the operator as it emerges from between the partition members 9.

Preferably alternate levers 29 are bent upward near their forward ends as indicated at 37 so as to produce staggered relation of the buttons 34 in two different planes, when 105 the levers are in the retracted position, so that any particular button can be selected with maximum ease and depressed without interfering with any of the other levers.

In Fig. 6 we have shown a partition wire 110 9 having a jacket or covering 38 of any soft material to minimize the liability of scratching of the records when they are being introduced in the file or abstracted therefrom. The jacket 38 as shown is in the form of a tube which, if desired, can be manufactured in any suitable manner, and then slipped onto the wire before or after the wire is bent into the partition form.

From the foregoing it is clear that the end 120 members 1, 2 and rods 3, 4, 5, in one instance, and 3, 4, 5, 6 in another instance form a frame and that the partition wires are strung on the frame. The slots 8 prevent the wires from slipping along the rods.

125 We claim:

1. In a record file, the combination of end members, rods fastened at their ends to the end members, wires strung from rod to rod and each bent at one end around one of the 130

- rods, the other ends of said wires being secured to the wires intermediate of two of said rods, and means on the rods to prevent the wires from slipping along the rods.
- 5 2. In a record file, the combination of end members, upper and lower rods fastened at their ends to the end members, another rod fastened to the end members rearward of the lower rod, wires extending from the rear 10 rod aslant upward and forward over the upper rod, thence downward under the lower rod, thence aslant upward and rearward to the respective wires and fastened thereto, and means on the rods to prevent the wires 15 from slipping along the rods.
3. In a record file, skeleton partitions, means to hold the partitions in spaced relation, and pivotally mounted levers in the 20 spaces between the partitions, each of said levers having upturned flanges at its edges spaced from one another at its forward portion and bent together at its rear portion so that said rear portion will be free from engagement with the partitions.
- 25 4. In a record file, skeleton partitions having front and rear members, means to hold the partitions in spaced relation, and pivotally mounted levers having their forward ends inserted between adjacent front par-

tition members and their rear ends between 30 adjacent rear partition members, the forward portions of the levers being provided with upturned flanges and being substantially as wide as the distance between adjacent front partition members, and the rear 35 portions of said levers being narrower than the forward portions thereof so as to be free from engagement with the rear partition members.

5. In a record file, end members, a shaft 40 fastened at its opposite ends to the end members, front and rear partition members, and record-supporting levers arranged at intervals between the end members, each lever having a downwardly bent portion curled 45 under the bottom of the lever to form an openable and closable eye engaging the shaft and the front and rear partition members forming guides for the opposite ends of the levers. 50

In testimony whereof, we have hereunto set our hands at Los Angeles, California, this 25th day of March, 1918.
